UNITED STATES PATENT OFFICE

156,421

EXHAUST PIPE EXTENSION

Leonard Kaplan, Chicago, Ill.

Application August 8, 1949, Serial No. 4,350

Term of patent 14 years

(Cl. D14—6)

To all whom it may concern:

Be it known that I, Leonard Kaplan, a citizen of the United States, residing at Chicago, county of Cook, State of Illinois, have invented a new, original, and ornamental Design for an Exhaust Pipe Extension, of which the following is a specification, reference being had to the accompanying drawing, forming a part thereof.

Fig. 1 is a front perspective view of an exhaust pipe extension showing my invention.

Fig. 2 is a rear perspective view thereof, and Fig. 3 is a bottom plan view thereof.

I claim:

The ornamental design for an exhaust pipe extension, as shown.

LEONARD KAPLAN.
